ABSTRACT OF THE DISCLOSURE

An inertia switch is mounted on the pit cushion of a pin setting machine to energize the "new set" solenoid of the machine through a relay equipped with a holding circuit. A deactivating switch in the coil circuit of the relay is operated by a cam on a shaft of the machine which makes one revolution in each pin-setting cycle to open the holding circuit and deenergize the relay as soon as the machine starts operating.

BACKGROUND OF THE INVENTION

This invention relates to automatic pin setters, and particularly to an improvement in the cycle triggering mechanism of a pin setting machine of the type disclosed in Pat. No. 2,949,300 to William F. Huck et al.

The known machine is equipped with a movably mounted cushion in the pit at the rear end of the alley. When the cushion is struck by a thrown ball or a pin with sufficient force, a mechanical linkage attached to the cushion pulls a trigger which starts the pin-setting cycle of the machine. If the cushion is not struck with a force sufficient to trigger the machine cycle, a push button switch at the front end of the machine may be closed by the bowler to energize a "new set" solenoid which pulls the trigger independently of the cushion action and starts the cycle.

If a ball is thrown with unusual speed to impart a very heavy blow to the cushion, the linkage and other mechanical elements of the automatic machine may be damaged. It is therefore common practice to equip the known pin setter with a shear pin arranged to interrupt the connection between the pit cushion and the pin-setting mechanism proper and to protect the latter. The alley must be shut down for several hours while a broken shear pin is being replaced.

The object of the invention is the provision of an improved triggering arrangement which responds to lightly thrown balls to initiate the pin-setting cycle, and which is immune to damage by heavy balls thrown with great force, and thus makes shear pins unnecessary.

SUMMARY OF THE INVENTION

With this object and others in view, as will hereinafter become apparent, this invention, in one of its more specific aspects, provides the known automatic pin setter with an inertia switch mounted on the pit cushion in such a position as to close the circuit of a relay in response to an even slight movement of the cushion. Once energized, the relay is kept energized by a holding circuit and closes contacts arranged in parallel with the afore-mentioned push button switch for the "new set" solenoid. As soon as the machine starts moving in its pin-setting cycle, the relay is deenergized to prevent accidental triggering of an additional cycle in response to the vibration of the machine before the initially triggered cycle is completed.

Other features, additional objects, and many of the attendant advantages of this invention will readily be appreciated as the same becomes better understood by reference to the following detailed description of a preferred

embodiment when considered in connection with the appended drawing.

BRIEF DESCRIPTION OF THE DRAWING

5 In the drawing:

FIG. 1 shows a bowling alley equipped with an automatic pin setter of the invention in a fragmentary side elevation; and

10 FIG. 2 is a schematic of the cycle triggering mechanism of the invention.

DESCRIPTION OF THE PREFERRED EMBODIMENT

15 Referring initially to FIG. 1, there is seen a bowling alley equipped with an automatic pin setter which is identical with that more fully described in Pat. No. 2,949,300 to William F. Huck et al., except as specifically stated hereinbelow. The known portion of the pin setter has been shown in the drawing only to the extent needed for a understanding of this invention. Primed reference numerals in this application relate to elements carrying the same numeral in the patent.

20 An alley bed 1' normally carries pins near its near end, adjacent a pit 2'. A console 8 at the front end of the alley is provided with a normally open push button switch 623'. A pit cushion 135' is mounted in the pit 2' on two bars 136' at the sides of the alley, only one bar being seen in the drawing. The bars 136' are suspended from triangular plates 132' movable on the stationary machine frame, not itself shown. Dashpots 138a' attached to the rods 136' prevent swinging motion of the cushion 135' after it has been struck by a bowling ball or a pin.

25 Only the casing 164' of a gear box and certain elements mounted thereon have been shown of the pin-setting mechanism proper. The gearing in the box 164' is driven by an input shaft 165' when a clutch 159' is engaged, the input member of the clutch being a pulley 161' driven by a V-belt 160' and a nonillustrated electric drive motor.

30 35 When the clutch 159' is engaged, several output shafts on the gear box casing 164' revolve at different speeds. Cams on the output shafts operate the working elements of the pin setter and ultimately disengage the clutch 159' when the pin setting cycle is completed. Only the output shaft 176' is seen in FIG. 1. It rotates at such a speed as 40 to make one revolution during the cycle.

35 45 The clutch 159' is engaged by mechanical elements not seen in the drawing which are triggered in the known apparatus by a mechanical linkage attached to the bars 136', but not used in the modified pin setter of this invention. The gear box casing 164' also carries a "new set" solenoid 580' connected by a link 581' to the triggering device and permitting the clutch 159' to be engaged by a bowler by means of the push button switch 623'.

50 55 Except for the absence of the mechanical linkage connecting the rods 136' to the triggering device for the clutch 159', the apparatus described so far is common to this invention and the afore-mentioned patent.

60 65 The lower ends of the rods 136' each carry an inertia switch 10, the protective housing of one switch being seen in FIG. 1. A normally closed deactivating switch 12 is mounted on the gear box casing 164' near the shaft 176', and its actuating element 14 is engaged by a radial cam 16 on the shaft 176' during the cycling of the pin setter. The switch actuating element 14 is released only when the pin setter cycle is completed and the clutch 159' has been disengaged. FIG. 1 shows the cam 16 in its inoperative position.

70 75 The schematic of FIG. 2 shows the circuit connecting the switches 10 and 12 with each other and with the "new set" solenoid of the known machine. The solenoid 580' and its manually operated switch 623' are arranged in

series between the main power lines 600', 601' of the machine.

I provide an electromagnetic relay whose coil 18, when energized, closes two normally open switches 20, 22. The switch 20 is arranged in parallel to the switch 623'. The primary winding 24 of a step-down transformer 24 is connected to the main lines 600', 601'. One terminal of the secondary transformer winding 26 is connected to one terminal of the coil 18. The other transformer terminal is connected to one lead of each inertia switch 10 and to one contact of the relay switch 22. The other contact of the switch 22 and the other lead of each inertia switch 10 are connected to the other terminal of the coil 18 through the normally closed, cam-operated switch 12.

The inertia switches 10 are of the conventional type having an approximately banana-shaped glass envelope 28, and leads sealed into one end of the envelope which encloses a drop of mercury 30. The glass envelope 28 is mounted on the associated bar 136' in such a position that any light blow against the cushion 135' causes the mercury drop 30 to be projected toward the leads of the switch 10 to connect the same at least momentarily.

As is evident from FIG. 2, closing of the switch 10 causes the coil 18 to attract its armature, thereby closing the holding switch 22 and keeping the coil 18 energized if the mercury drop 28 returns to the illustrated position. The solenoid 580' is energized through the closed switch 20 and triggers engagement of the clutch 159'. As soon as the input shaft 165' starts rotating and drives the shaft 176', the cam 16 opens the switch 12, and the coil 18 is deenergized to release its armature. The pin setting mechanism performs its normal operating cycle and ultimately disengages the clutch 159', the deactivating switch 12 being simultaneously closed by its non-illustrated return spring when the actuating element 14 on the switch is aligned with the low in the cam 16.

With the switches returned to the respective positions shown in FIG. 2, the triggering mechanism is ready for the next ball or pin striking the cushion 135'.

The position of each switch 10 on its bar 136' is best determined by trial and error. The envelope 28 of each switch 10 should normally be elongated in a plane parallel to that of FIG. 1, and the inclination of the envelope in this plane will determine the sensitivity of the switch. It is readily selected to make the triggering mechanism responsive to the striking of the cushion by a ball, but insensitive to maintenance personnel walking near the pin spotting apparatus. The vibrations caused by the heavy actuating mechanism in the gear box casing 164' and attached to the elements in the casing are normally sufficient to close the switches 10, and the deactivating switch 12 is necessary under these conditions to prevent undesired energizing of the solenoid 580'.

A lightly thrown ball may close the switches 10 for too short a period to cause proper operation of the solenoid 580', and the holding circuit mainly consisting of the switch 22 and associated conductors is essential to reliable operation of the triggering device at highest sensitivity of the switches 10. When two switches 10 are mounted at opposite ends of the cushion 135', this sensitivity has been found to be greatly increased over the use of a single switch 10.

The electrical circuit elements introduced in the known pin setter by this invention are rugged enough to have a long useful life. The relay shown in FIG. 2 may be mounted in any convenient location on the machine itself or remotely. The deactivating switch 12 may be opened after the initiating of the pin setting cycle by a switch operating element other than the cam 16 specifically illustrated since many mechanical parts of the actu-

ating mechanism move once back and forth during the cycle. If the triggering mechanism is cocked by the actuating mechanism only late in the cycle, the opening of the deactivating switch 12 may be delayed correspondingly after the initiating of the cycle, but the switch 12 should not be closed again much before the actuating mechanism comes to a standstill.

What I claim is:

1. In an automatic pin setter having a mechanical actuating mechanism for operating the pin setter in a cycle, a triggering mechanism for initiating a cycle of operation of the actuating mechanism, a pivotally mounted pit cushion adapted to be struck by a bowling ball and to be pivoted by the impact of the ball, connecting means connecting the pit cushion to the triggering mechanism for triggering said cycle of operation in response to the pivoting of said cushion, and electrical auxiliary means for operating the triggering mechanism, the improvement in the connecting means which comprises:

(a) an inertia switch mounted on said pit cushion in a position to cause operation of said inertia switch when said pit cushion is pivoted by a bowling ball; and

(b) connecting circuit means operatively interposed between said inertia switch and said electrical auxiliary means for energizing the electrical auxiliary means and for thereby triggering said actuating mechanism when said inertia switch is operated, said connecting circuit means including

(1) holding circuit means for keeping said electrical auxiliary means energized after operation of said inertia switch ceases, and

(2) deactivating means for preventing energizing of said electrical auxiliary means by said inertia switch and by said holding circuit means while said actuating mechanism is in operation.

2. In a pin setter as set forth in claim 1, said connecting circuit means including an electromagnetic relay having a coil and two switches operated by said coil, said pin setter including a source of electrical current, said electrical auxiliary means and one switch of said relay being arranged in series circuit with said source, and the other switch of said relay being arranged in series circuit with said coil and constituting a portion of said holding circuit means.

3. In a pin setter as set forth in claim 2, said deactivating means including a deactivating switch in series circuit with said coil, and switch operating means drivingly connected to said actuating mechanism for opening said deactivating switch after the initiating of said cycle and for closing said switch at the conclusion of said cycle.

4. In a pin setter as set forth in claim 1, said inertia switch including an envelope of insulating material elongated in the direction of pivoting movement of said pit cushion, two leads sealed into one longitudinal end of said envelope, and a drop of mercury movable in said envelope toward and away from said leads in said direction of pivoting movement.
